U. S. PATENT OFFICE.

No. 88.

1861.

Whole No. 1,453.

IRON DOORS.

GARRETTSON SMITH AND HENRY BROWN, OF PHILADELPHIA, PA.,

ASSIGNORS TO NORTH, CHASE & NORTH, OF SAME PLACE.

Letters Patent for a Design No. 88, dated July 16, 1861.

SPECIFICATION.

TO ALL WHOM IT MAY CONCERN:

Be it known, that we, GARRETTSON SMITH and HENRY BROWN, of the city and county of Philadelphia, and State of Pennsylvania, have invented or produced a new and original design for Iron Doors; and we do hereby declare that the following is a full and exact description of the same, reference being had to the accompanying drawing, in which—

C represents an oven door unfinished.

α α α, (small) mouldings.

What we claim as our invention, and desire to secure by Letters Patent, is—

The design and configuration of the mouldings α α α, forming an ornamental design for iron doors, and we desire to limit our claim to the said design.

GARRETTSON SMITH,
HENRY BROWN.
